APPARATUS FOR TRANSPORTING VISCOSO OILS

Shelby D. Lawson, Bartlesville, Okla., assignor to Phillips Petroleum Company, a corporation of Delaware

Application November 10, 1955, Serial No. 546,211

1 Claim. (Cl. 23—288)

This invention relates to a method of and apparatus for preparing oils of high viscosity for transportation through a pipe line.

It is known that crude oils produced from several fields are waxy and have high pour points. For example, Roosevelt crude oil from Uintah Basin has a pour point of approximately 100° F. Oils of this type obviously cannot be transferred through pipe lines because they are too viscous to flow at normal temperatures. Heretofore, oils of this type generally have been transported by tank cars or trucks. Such overland transportation is relatively expensive compared with pipe line transportation and for this reason is not desirable. One method which has been proposed for transporting high viscous oils by pipeline is to heat the oil at intermediate locations along the pipe line to maintain the temperature of the oil above its pour point. Heaters employed for this purpose can be operated by withdrawing for fuel a portion of the oil being transmitted. However, this procedure may result in the loss of as much as 15 to 20 percent of the crude oil. Another method proposed to reduce the pour point of the oil employs thermal visbreaking. However, this procedure results in substantial quantities of gases being produced. Still another method which has been proposed involves diluting the oil with a natural gasoline. However, this procedure requires a supply of natural gasoline at the pumping station, which in many fields is not available.

In accordance with the present invention a system is provided to reduce the viscosity of crude oil sufficiently to permit the oil to be transported through a pipe line. A portion of the crude oil to be transported is directed to the inlet of a catalytic cracking unit. The products from the cracking unit are mixed with the remainder of the crude oil to produce a blend having a pour point sufficiently low to permit passage through a pipe line at ambient temperature conditions. The cracking can be accomplished by fluid catalyst cracking, moving bed catalytic cracking, or fixed bed catalytic cracking. In general, the fluid technique is preferred. Although it is realized that any cracking process employed on crude oil has a detrimental effect on the straight run distillates produced therefrom, the present day use of hydrogenation in refining substantially eliminates this undesired effect. By employing catalytic cracking, a maximum amount of products in the gasoline range is produced with a minimum loss of product as gases. The produced gases can be employed as fuel in the cracking unit.

Accordingly, it is an object of this invention to provide a method of preparing viscous oils for transportation through pipe lines.

Another object is to provide apparatus to treat viscous oils for subsequent transportation through pipe lines.

Other objects, advantages and features of the invention should become apparent from the following detail description of a present preferred embodiment of the invention taken in conjunction with the accompanying

2

drawing which is a schematic representation of apparatus employed to carry out the method of this invention.

Referring now to the drawing in detail, there is shown an inlet conduit 10 which delivers crude oil from a producing field to a storage tank 11. Tank 11 is supplied with a heating coil 12 which may be needed to maintain the crude oil fluid if it is stored for prolonged periods in cool temperatures. A portion of the oil removed from tank 11 is directed through conduits 13, 14 and 15 to an accumulator 16. The remainder of the oil removed from tank 11 passes through conduit 13, a heat exchanger 17 and a conduit 18 to the inlet of a fluid catalytic cracker reactor 19. Regenerated cracking catalyst is directed from a regenerator 20 through a conduit 21 to reactor inlet conduit 18. Coked catalyst from reactor 19 is removed through a conduit 23. Conduit 23 communicates with a conduit 24 which in turn communicates with the inlet of regenerator 20. Air is introduced through conduit 24 to burn the carbon deposits off the catalyst in regenerator 20.

Steam or other stripping fluid is supplied to reactor 19 through a conduit 26 to remove cracked products which may be adsorbed on the catalyst. The cracked products are removed from reactor 19 through a conduit 28 which passes through an air cooler 29 and heat exchanger 17 to conduit 15. Gases in the top of accumulator 16 are withdrawn for use as fuel through a conduit 30. A predetermined pressure is maintained in accumulator 16 by a pressure regulating valve 31 in conduit 30.

The fluid in accumulator 16 thus comprises a blend of the original crude oil and the products from reactor 19. This blended oil is directed through a conduit 32 to an outlet storage tank 33. The oil is removed as desired from tank 33 through a conduit 34 which communicates with a pipe line 35.

Flue gases from regenerator 20 are removed through an overhead line 37 which has a pressure regulating valve 38 therein. The heat content of these gases can be utilized to generate steam to supply conduit 26 or to heat tank 11. Regenerator 20 may be supplied with a cooling coil 39 which has water circulated therethrough to prevent excessive heat rises in the regenerator. The steam produced by water being heated in coil 39 can also be employed to heat tank 11 or to supply stripping material to reactor 19.

It is desired that the regenerator be operated at a temperature in the range of 1040 to 1090° F. At higher temperatures the catalyst tends to be deactivated, and at lower temperatures the regeneration takes place at an excessively slow rate. It is desired that the reactor be maintained at a temperature in a range from 890 to 930° F. At higher temperatures excessive quantities of gas and coke are produced, and at lower temperatures the cracking takes place too slowly. In general, there is about a 4 to 5% increase in liquid volume when crude is passed through the cracking unit. It is preferred that accumulator 16 be maintained at a temperature of approximately 100° F. and at a pressure of approximately 50 p. s. i. g. This condenses all but about 5% by liquid volume of the cracked products. The ethane and lighter are removed as fuel gas. At lower pressures excessive amounts of gases are formed in the accumulator. Higher pressures generally are not objectionable but tend to increase the cost of the equipment. The catalyst can be any conventional cracking catalyst such as, for example, natural or clay catalysts comprising, in general, activated montmorillonite clays or synthetic catalysts which include silica base (silica-alumina, silica magnesia and silica zirconia) and alumina-base, such as, alumina-boria. The ratio of oil passed directly to accumulator 16 and to the cracking unit depends to a large extent on the pour point

of the crude oil being treated. If the pour point increases, a greater portion of the oil must be cracked to maintain a pumpable blend. Also the ambient temperature of the pipe line influences the required viscosity of the blended fluid. In general, the amount of crude oil directed to the cracking unit varies from about 5 to 30 percent. Obviously, less crude is cracked in the summer than in the winter.

As a specific example of the operation of this invention, it is assumed that a crude oil having a pour point of 100° F. is to be transported in moderate weather wherein a mixture having a pour point of 65° F., for example, can readily be passed through a pipeline. It is also assumed that crude is removed from tank 12 at a rate of 1000 barrels per hour. Fifteen percent of this crude, 150 barrels per hour, is directed to the cracking unit through conduit 18. The remaining 850 barrels per hour is passed directly to accumulator 16. The charge to the cracking unit results in the production of approximately 156 barrels per hour, based on equivalent liquid. Of this, approximately 8 barrels per hour, based on equivalent liquid, is "lost" as fuel gas. This gas contains most of the ethane and lighter. The remaining 148 barrels per hour (156-8) is blended with the original 850 barrels per hour in accumulator 16 to give a total blend of 998 barrels per hour. This blend has a pour point of approximately 65° F.

It should be apparent that moving bed and fixed bed catalytic cracking systems can also be employed in carrying out the process of this invention. These processes are, of course, well known to those skilled in the art and for this reason are not described in detail herein.

From the foregoing description it should be evident that there is provided in accordance with this invention an improved process to treat crude oils of high viscosity to render them capable of being transported through a pipe line. The essence of this invention is the catalytic cracking of a portion of the crude and the blending of the

cracked products with the remainder of the crude to obtain a mixture having a sufficiently low viscosity to be transported through a pipe line. The invention can be performed by a self-contained cracking unit located at an oil producing field. The process does not require any external diluent to reduce the viscosity of the oil to be transported.

While the invention has been described in conjunction with the present preferred embodiment it should be evident that it is not limited thereto.

What is claimed is:

Apparatus for preparing a viscous oil for transportation through a pipe line comprising an inlet oil storage tank, a fluid catalyst reactor, a heat exchanger, first conduit means to direct oil from said tank through said heat exchanger to the inlet of said reactor, a fluid catalyst regenerator, conduit means to direct spent catalyst from said reactor to said regenerator, means to introduce air into said regenerator, conduit means to direct regenerated catalyst from said regenerator to said reactor, an accumulator, conduit means to direct cracked products from said reactor through said heat exchanger in indirect heat exchange with the oil supplied to said reactor to said accumulator, conduit means to direct a predetermined amount of oil from said tank to said accumulator, and means to supply the blended products in said accumulator to a pipe line.
